UNITED STATES PATENT OFFICE.

OTIS F. REITER, OF RELAY, MARYLAND.

STONE-GATHERER.

1,300,018.

Specification of Letters Patent.

Patented Apr. 8, 1919.

Application filed June 2, 1917. Serial No. 172,494.

To all whom it may concern:

Be it known that I, OTIS F. REITER, a citizen of the United States, residing at Relay, in the county of Baltimore and State of Maryland, have invented certain new and useful Improvements in Stone-Gatherers, of which the following is a specification, reference being had to the accompanying drawings.

10 This invention relates to machines for gathering stones, and particularly to a machine of this character in the nature of a rake.

15 The general object of my invention is to provide a machine which will rake up the stones in a field and convey the stones to a conveyer trough or casing from which the stones may be carried in any suitable conveyer and disposed in a wagon traveling alongside of the gathering machine.

20 A further object is to provide a machine of this character having a plurality of raker teeth, a plurality of lifting teeth radially disposed around the axle of the machine and 25 moving upward and rearward over the faces of the raker teeth, and a plurality of conveyer teeth by which the stones as they are carried around by the lifting teeth are guided into a conveyer trough and an elevator trough.

30 A further object of the invention is to provide means whereby the lifting teeth may be so mounted upon the axle as to be readily replaced in case of breakage and in this connection to provide means which will tend to prevent breakage of the raker teeth and of the conveyer teeth by the blocking of stones between these teeth.

35 A further object is to provide means whereby the raker teeth may be lifted out of or into operative position.

40 Other objects will appear in the course of the following description.

45 My invention is illustrated in the accompanying drawings, wherein:

Figure 1 is a front elevation of a stone-gathering machine constructed in accordance with my invention, the frame being in section;

50 Fig. 2 is a longitudinal section of the construction shown in Fig. 1;

Fig. 3 is a vertical sectional view on the line 3—3 of Fig. 4;

55 Fig. 4 is a section on the line 4—4 of Fig. 3;

Fig. 5 is a side elevation of the conveyer chain;

Fig. 6 is a top view of the conveyer chain;

Fig. 7 is a fragmentary side elevation showing the bearing for the axle; 60

Fig. 8 is a vertical sectional view through the bearing;

Fig. 9 is a perspective detailed view of one of the trip teeth;

Fig. 10 is a fragmentary vertical sectional 65 view through the bracket 44 showing a trip tooth in the act of tripping.

Fig. 11 is an elevation of a portion of the shaft 12 showing in section the manner in which the members 15 are loosely supported 70 upon the shaft, the beams 11 and the bearings 60 being also in section;

Fig. 12 is a fragmentary sectional view on the line 12—12 of Fig. 11.

Referring to the drawings, 10 designates 75 a frame of any suitable construction, and including the longitudinally extending side beams 11, which are spaced from each other and braced in any suitable manner. Rotatably mounted between these beams 11 and, 80 of course, extending transversely of the frame, is an axle 12, the middle portion of this axle for any suitable distance between the wheels, being square as at 13. Mounted upon the ends of the axle are the traction 85 wheels 14, these traction wheels being connected to the axle by means of any suitable pawl and ratchet mechanism so that when the machine moves forward, rotation will be given to the axle, but when the machine is 90 backed up, the wheels 14 will move without reversely rotating the axle. Mounted upon the ends of the axle are supporting members 95 15, which are loosely mounted upon the axle as illustrated in Fig. 12, and permit the axle to rotate within the supporting members. Each supporting member is formed with a rearwardly opening socket 16 and a downwardly and rearwardly opening socket 17.

Disposed in the first named socket is the 100 rearwardly extending bar 18 and in the second named socket the downwardly and rearwardly extending bar 19. The rearwardly extending bars 18 are connected by means of a transversely extending bar 20 and the 105 bars 19 are connected at their ends by a transversely extending bar 21. Attached at their upper ends to the bar 20 and extending downwardly and forwardly in a curve are the raker teeth 22, which extend over the in- 110

ner face of the bar 21 and are riveted or otherwise attached thereto and extend beyond this bar 21, and are provided with raker teeth points 23 which are preferably made detachable and preferably made so that the angle of the points 23 may be changed. I have illustrated the raker teeth points 23 as being connected to the raker teeth by means of bolts 24 and beveled washers 23^a and such a construction permits of the change of conformation in the points and a change in the adjustment of the teeth 23.

The rake formed by the spaced raker teeth 15 normally rests upon the surface of the ground by its own weight, but the raker teeth may be lifted by means of a cable or cables 25 attached to one or both of the bars 18 and extending upward over a pulley or 20 like device 26 and then extending forward and wound upon a winding drum 27, which is rotated by means of a lever 28. Preferably this lever 28 is engaged with the winding drum by means of a pawl 29 engaging 25 with a ratchet 30. Any other axle of this character, however, may be used. By this means the raker teeth may be raised or depressed to any desired extent. The forward end of the frame 10 is supported upon bolsters in the usual manner, the lower bolster being supported upon any suitable steering wheel or wheels 31 and having a tongue 32 extending from the truck thus formed.

Mounted upon the square axle 12 are a 35 series of lifting teeth, each tooth being designated 33. These teeth are disposed in staggered relation to the teeth 22 and mounted upon the axle in the following manner. Engaging the axle and rotating therewith 40 are a plurality of disks 34, each of these disks being made in two sections A and B. Each of these sections is cut away so as to embrace half of the axle so that when the sections A and B are abutted against each 45 other, they will entirely embrace the axle and rotate therewith. The sections A and B may be held in engagement with each other in any suitable manner, as by longitudinally extending bolts 35. Each disk 34 formed of 50 the sections A and B is cut away at a plurality of points, as at 36, these recesses 36 being disposed in quartering relation to each other. If there be four recesses, as illustrated, the line which divides the section A from the 55 section B passes transversely through two of said recesses, as illustrated in Fig. 4 so that two of the bolts pass through the intersections of the sections A and B and two of the bolts 35 pass through solid portions of the 60 sections A and B. These disks 34 formed of the sections A and B are disposed with the plane *b* of division between the sections A and B extending alternately vertically and horizontally so that the joints between the 65 sections A and B of one disk 34 do not match

with the joints between the sections A and B of the next adjacent disks 34.

The lifting teeth 33 are attached to lifting teeth stubs 37, the inner end of each stub being bent to form an eye 38, which loosely surrounds the corresponding bolt 35. Thus the lifter teeth have a certain amount of pivotal movement but will rotate with the corresponding disk 34. The lifter teeth 33 are preferably detachably engaged with the 70 corresponding stubs 37 by means of bolts or like devices and preferably the lifter teeth are yieldingly held from movement within the corresponding recesses 36 by coiled springs 39, which bear at one end against upwardly 75 extending lugs 40 formed upon the disks 34, each spring at its other end bearing against the outer end of the corresponding stub 37 and being connected thereto in any suitable manner. These springs 39 will prevent the 80 lifter teeth from being broken away when the lifter teeth strike the stones which have been gathered up by the raker teeth and start to lift them.

The lifter teeth rotate with the axle 12 as 85 before stated and preferably these lifter teeth are curved in the direction of their movement so that as the lifter teeth move upward, they will carry up with them the stones or other material gathered upon the 90 raker teeth and when the lifter teeth pass the raker teeth, they will be in an approximately horizontal position and will carry the stones up with them. In order to provide means upon which the stones may be 95 discharged, after they have been lifted by the raker teeth, I provide the conveyer bars designated 41. These bars at their rear ends are formed with sleeves 42 which loosely embrace the disks 34 and are disposed between 100 the lifter teeth 33, as shown best in Fig. 3. As illustrated, the bars 41 are riveted to the sleeves or rings 42, and sufficient clearance is 105 left between the rings 42 and the conveyer bars so as to permit the passage of said lifter 110 teeth between said bars. These bars 41 normally extend downward and forward toward an elevator trough or box 43 mounted upon the frame of the machine and mounted upon this box or casing 43 are brackets 44 115 which support a transversely extending rail 45. Hingedly mounted upon this rail 45 are a plurality of trip teeth 46, the hinges being so arranged that the trip teeth may turn 120 downward to the position shown in Fig. 10. In order to draw the trip teeth back to their 125 normal position with the extremities of the trip teeth extending beneath the extremities of the conveyer bars 41, I preferably provide each of the trip teeth 46 with a pin 47, which extends downward through an opening 48 in the rail 45, each of these pins or bolts 47 having a head 49 at its lower end and between this head and the rail 45 is disposed a coiled 130 spring 50 whose tension causes the members

46 to be drawn back to their normal positions. Preferably the extremities of the trip teeth 46 are formed with upwardly extending lateral flanges 51, which engage 5 with the corresponding conveyer bars 41 so as to hold the trip bars in proper alinement with the corresponding conveyer bars. The purpose of this construction is to permit the conveyer bars 41 and the trip teeth 46 to 10 move downward in case a stone or other piece of material become blocked between the lifter teeth and the conveyer bars, as illustrated in Fig. 10. In this case, unless provision be made for the downward movement of one or more conveyer bars 41, either 15 the lifting teeth will be broken or the conveyer bars will be broken but by this construction when an object is caught between a lifter tooth and one or more of the conveyer bars 41, the trip teeth 46 will give permitting 20 the conveyer bar to move downward to such a position that the stone will be discharged upon the ground. The depending tooth may then be carried back to its original 25 position above the tooth 46 by hand. It will, of course, be understood that the springs 50 are sufficiently strong to support the trip teeth 46 in their normal position and thus support the conveyer bars 41 in 30 their normal positions against the weight of stones which may be thereon or against ordinary pressure.

The conveyer trough 43 extends transversely of the frame 10 in advance of the traction wheels and is suitably mounted on the frame so as to be disposed on a lower level than the frame and the rear side of the conveyer trough opened so that the trip teeth 46 will discharge into the trough. 35 Preferably the side walls and bottom wall of the trough are formed of longitudinally extending slats of wood or metal but I do not wish to be limited to this. Operating along the bottom of this conveyer trough is 40 an endless conveyer 52 formed of links, as illustrated in Fig. 6, these links being pivotally connected to each other by means of transverse bolts 53. Certain of the links are provided with ears 54 and pivoted between 45 these ears are the upwardly extending teeth 55 having rearwardly extending members 56 engaging over the cross bar of the links. This conveyer 52 extends the full length of the trough 43 and discharges onto an upwardly 50 extending conveyer 57 mounted in an upwardly extending trough or casing 58, which is supported upon the frame in any suitable manner and is preferably supported so that it may be raised or lowered. The 55 upper end of this casing 58 may be connected to the frame by cables 59, or any other suitable manner. Suitable driving means are illustrated whereby the endless conveyers 52 and 57 may be operated by the rotation of 60 the traction wheels of the machine. Inasmuch

as a construction of this kind is common and well known, I have not deemed it necessary to describe this transmission gearing.

Preferably the shaft 12 passes through 70 journal boxes 60 carried on the frame of the machine. These journal boxes may be constructed in any suitable manner but are preferably provided with dust caps of the form illustrated in Figs. 7, 8 and 11. Each dust cap 75 61 consists of two mating half sections, each section being formed with a semi-circular opening which, when the sections are joined define a circular opening. Each of these sections is formed with an angular flange on its outer face, designated 62, the flange on the upper section being semi-circular in form and the flange on the lower section being interrupted as at 63. Operating within the annular guideway defined by these flanges 62 are 80 washers 64 having each a square opening which surrounds the square end of the shaft. It will, therefore, be seen that these washers are supported on the shaft and the washers in turn rotate within the guideway formed 85 within the annular flanges 62. Dust, dirt, or other matter will drop out through the opening 63. I do not wish to limit myself to this particular form of dust cap or journal bearing, as other forms may be used, if desired. 90

In Figs. 11 and 12 I show the manner in which the members 15 are supported for rotation around the shaft 12. As illustrated, a relatively hard bearing member 65 surrounds the squared portion of the shaft 12. 100 Each member 15 is cut away to surround the shaft and disposed within this cut-away portion of each member 15 is a bearing ring 66 of relatively hard metal, this bearing ring 66 being formed at opposite points with 105 projections 67 which extend into recesses formed in the inner face of the member 15. Thus the bushing 66 or bearing ring may be readily renewed whenever worn or the bearing 65 may be readily renewed. Washers 110 68 are disposed on each side of each member 15, as illustrated in Fig. 11, and these washers and the members 15 with their bearing rings, etc., are held in place by means of a cotter pin 69 passing through the shaft. 115

It is necessary, in this machine, that the axle be kept from sliding laterally with relation to the frame. For instance, if the machine be on a hillside and the right hand side of the machine were down hill, the 120 tendency of the axle would be to slide as far as possible against the right hand side of the frame, but inasmuch as the axle is square on each side of the bearings 60, the axle will bear against the bearing on both 125 sides of the frame, each side thus getting an equal strain. The axle and all that is on it must not slip laterally to any appreciable extent lest the several rake teeth, the lifter arms, the carrier teeth and other like 130

parts get out of proper alignment. Hence it is very important that provision be made preventing any lateral slip of the axle relative to the frame, but at the same time, of course the axle should rotate freely.

The operation of the invention will be obvious from what has gone before. The raker teeth 22, with their points 23, will gather up the stones, the points 23 running slightly below the surface of the ground so as to dig up stones therefrom and as these stones gather upon the raker teeth, they will be lifted by the rotatable lifting teeth 33. As the lifting teeth move upward along the raker teeth, they will carry the stones upward and eventually discharge them upon the conveyer bars 41 by which the stones will be directed onto the trip teeth 46 and by these teeth be carried to the elevator box or casing 43. The endless carriers disposed in the elevator boxings or casings 43 and 57 will carry the stones upward and discharge them into a wagon traveling alongside the machine. In case stones jam between the lifting teeth 33 and the conveyer bars 41, one or more of the conveyer bars will move downward, the trip teeth 46 giving away at this time, as before described, and then the depressed conveyer bars may be lifted again to their original positions by hand, or suitable mechanism may be provided for that purpose. It will be understood that the points 23 on the raker teeth may be angularly adjusted in any suitable manner by the use of a washer 23^a which is wedge-shaped in form and which may be rotated so as to change the angle of the points.

While I have illustrated certain details of construction which I believe to be particularly effective for the purpose intended, I obviously do not wish to be limited to these details, as the mechanism may be varied in many ways without departing from the spirit of the invention.

Having described my invention, what I claim is:

1. In a stone gatherer, a supporting frame, a truck upon which the frame is mounted, a rotatable axle, a series of downwardly and forwardly curved raker teeth operatively supported rearward of the axle, a series of rotatable lifting teeth mounted upon the axle to rotate therewith and moving upward and rearward past the raker teeth, and conveyer bars upon which the raker teeth discharge disposed in staggered relation to the raker teeth and said bars having frictional engagement at their rear ends with the axle, the forward ends of the bars being yieldingly held against rotation with the axle.

2. In a stone gatherer, a supporting frame, a rotatable axle, a series of downwardly and forwardly curved raker teeth operatively supported rearward of the axle,

a series of rotatable lifting teeth mounted upon the axle to rotate therewith and moving upward and rearward past the raker teeth, conveyer bars upon which the raker teeth discharge disposed in staggered relation to the raker teeth, said conveyer bars having frictional operative engagement with the axle, whereby the conveyer bars may rotate with the axle when free to move, and members upon which the conveyer bars discharge and supporting the forward ends of the conveyer bars, said members being yieldingly held from downward movement. 70 75

3. In a stone gatherer of the character described, a supporting frame, a truck upon which the frame is mounted, a rotatable axle, a series of raker teeth disposed rearward of the rear axle and disposed downward and forward and operatively supported upon the rear axle, a series of sets of lifter teeth mounted to rotate with the rear axle, each set comprising a plurality of radially directed raker teeth, said lifter teeth as they move upward and rearward coacting with the raker teeth to lift the stones thereon, a series of fixed conveyer bars having staggered relation to the lifter teeth and having their rear ends extending over the axle, said conveyer bars extending forward and downward, a transversely extending carrier onto which the stones are discharged from the conveyer bars, and means for yieldably supporting the forward ends of the conveyer bars so as to permit said ends to move downward in case a stone 100 locks between the lifter teeth and the conveyer bars. 90 95

4. In a stone gatherer of the character described, a supporting frame, a front truck upon which the frame is mounted, a rotatable rear axle, a series of raker teeth disposed rearward of the rear axle and disposed downward and forward and operatively supported upon the rear axle, a series of sets of lifter teeth mounted to rotate with the rear axle, each set comprising a plurality of radially directed raker teeth, said lifter teeth as they move upward and rearward coacting with the raker teeth to lift the stones thereon, a series of fixed conveyer bars having staggered relation to the lifter teeth and having their rear ends supported above the axle, said conveyer bars extending forward and downward, a transversely extending carrier onto which the stones are discharged from the conveyer bars, means for yieldingly supporting the forward ends of the conveyer bars so as to permit said ends to move downward in case a stone 110 locks between the lifter teeth and the conveyer bars, said means comprising trip teeth hingedly mounted and having their rear ends extending beneath the conveyer bars, and springs yieldingly holding the trip teeth in a normal position. 115 120

125

130

5. In a stone gatherer of the character described, a supporting frame, a front wheeled truck supporting the forward end of the frame, a rotatable axle mounted upon the rear end of the frame, traction wheels connected to rotate with the rear axle, members loosely mounted upon the rear axle and having rearwardly extending arms and downwardly and rearwardly extending arms, downwardly and forwardly extending teeth operatively supported upon said arms and constituting a rake, means for raising or lowering the rake, and a plurality of sets of lifting arms mounted upon the axle for rotation therewith, each set consisting of a plurality of radially disposed arms coacting with the rake to lift stones therefrom as the teeth move upward and rearward, and means for receiving the stones from said raker teeth as they move forward and downward. 65
- 10 6. In a stone gathering machine, a supporting frame, an axle rotatably mounted in the frame, traction wheels rotating with the axle, said axle being many-sided in cross section, a downwardly and forwardly extending rake operatively supported rearward of the axle, a plurality of disks mounted upon the axle to rotate therewith, and a plurality of sets of lifting teeth, each set comprising a plurality of radially disposed teeth, the teeth of each set being operatively connected to one of said disks. 70
- 15 7. In a stone gathering machine, a supporting frame, an axle rotatably mounted in the frame, traction wheels rotating with the axle, said axle being many-sided in cross section, a downwardly and forwardly extending rake operatively supported rearward of the axle, a plurality of disks mounted upon the axle to rotate therewith, a plurality of sets of lifting teeth, each set comprising a plurality of radially disposed teeth, the teeth of each set being operatively connected to one of said disks, and springs holding the teeth in normal position with relation to the disk. 75
- 20 8. In a stone gathering machine, a supporting frame, a transversely extending rotatable axle mounted on the frame, traction wheels operatively connected to the axle to rotate therewith, said axle being square in cross section for a portion of its length, a rake comprising downwardly and forwardly extending rake teeth operatively supported upon the axle and disposed rearward thereof, a plurality of disks mounted upon the axle to rotate therewith, each disk formed in two sections and each disk having a plurality of inwardly extending recesses, the dividing line between the two sections extending across two of said recesses, said disks being set upon the axle so as to break joints, bolts passing longitudinally through all of said disks and disposed through said recesses, a plurality of sets of lifting teeth operatively pivoted to said bolts, springs disposed in the recesses and holding the lifting teeth in a normal position but yielding against impact of the lifting teeth with stones, each set of lifting teeth being spaced from the adjacent sets, sleeves loosely surrounding the disks and disposed between the lifting teeth, downwardly and forwardly extending stone conveying bars attached to said sleeves and between which the lifting teeth pass. 80
- 25 9. In a stone gathering machine, a supporting frame, a transversely extending rotatable axle mounted on the frame, traction wheels operatively connected to the axle to rotate therewith, said axle being square in cross section for a portion of its length, a rake comprising downwardly and forwardly extending rake teeth operatively supported upon the axle and disposed rearward thereof, a plurality of disks mounted upon the axle to rotate therewith, each disk formed in two sections and each disk having a plurality of inwardly extending recesses, the dividing line between the two sections extending across two of said recesses, said disks being set upon the axle so as to break joints, bolts passing longitudinally through all of said disks and disposed through said recesses, a plurality of sets of lifting teeth operatively pivoted to said bolts, springs disposed in the recesses and holding the lifting teeth in a normal position but yielding against impact of the lifting teeth with stones, each set of lifting teeth being spaced from the adjacent sets, sleeves loosely surrounding the disks and disposed between the lifting teeth, downwardly and forwardly extending stone conveying bars attached to said sleeves and between which the lifting teeth pass. 85
- 30 10. In a stone gathering machine, a supporting frame, an axle rotatably mounted in the frame, traction wheels rotating with the axle, said axle being many-sided in cross section, a downwardly and forwardly extending rake operatively supported rearward of the axle, a plurality of disks mounted upon the axle to rotate therewith, and a plurality of sets of lifting teeth, each set comprising a plurality of radially disposed teeth, the teeth of each set being operatively connected to one of said disks. 90
- 35 11. In a stone gathering machine, a supporting frame, an axle rotatably mounted in the frame, traction wheels rotating with the axle, said axle being many-sided in cross section, a downwardly and forwardly extending rake operatively supported rearward of the axle, a plurality of disks mounted upon the axle to rotate therewith, a plurality of sets of lifting teeth, each set comprising a plurality of radially disposed teeth, the teeth of each set being operatively connected to one of said disks, and springs holding the teeth in normal position with relation to the disk. 95
- 40 12. In a stone gathering machine, a supporting frame, a transversely extending rotatable axle mounted on the frame, traction wheels operatively connected to the axle to rotate therewith, said axle being square in cross section for a portion of its length, a rake comprising downwardly and forwardly extending rake teeth operatively supported upon the axle and disposed rearward thereof, a plurality of disks mounted upon the axle to rotate therewith, each disk formed in two sections and each disk having a plurality of inwardly extending recesses, the dividing line between the two sections extending across two of said recesses, said disks being set upon the axle so as to break joints, bolts passing longitudinally through all of said disks and disposed through said recesses, a plurality of sets of lifting teeth operatively pivoted to said bolts, springs disposed in the recesses and holding the lifting teeth in a normal position but yielding against impact of the lifting teeth with stones, each set of lifting teeth being spaced from the adjacent sets, sleeves loosely surrounding the disks and disposed between the lifting teeth, downwardly and forwardly extending stone conveying bars attached to said sleeves and between which the lifting teeth pass, a transversely extending conveyer mounted upon the frame of the machine and including a conveyer 100
- 45 13. In a stone gathering machine, a supporting frame, an axle rotatably mounted in the frame, traction wheels rotating with the axle, said axle being many-sided in cross section, a downwardly and forwardly extending rake operatively supported rearward of the axle, a plurality of disks mounted upon the axle to rotate therewith, and a plurality of sets of lifting teeth, each set comprising a plurality of radially disposed teeth, the teeth of each set being operatively connected to one of said disks, and springs holding the teeth in normal position with relation to the disk. 105
- 50 14. In a stone gathering machine, a supporting frame, a transversely extending rotatable axle mounted on the frame, traction wheels operatively connected to the axle to rotate therewith, said axle being square in cross section for a portion of its length, a rake comprising downwardly and forwardly extending rake teeth operatively supported upon the axle and disposed rearward thereof, a plurality of disks mounted upon the axle to rotate therewith, each disk formed in two sections and each disk having a plurality of inwardly extending recesses, the dividing line between the two sections extending across two of said recesses, said disks being set upon the axle so as to break joints, bolts passing longitudinally through all of said disks and disposed through said recesses, a plurality of sets of lifting teeth operatively pivoted to said bolts, springs disposed in the recesses and holding the lifting teeth in a normal position but yielding against impact of the lifting teeth with stones, each set of lifting teeth being spaced from the adjacent sets, sleeves loosely surrounding the disks and disposed between the lifting teeth, downwardly and forwardly extending stone conveying bars attached to said sleeves and between which the lifting teeth pass, a transversely extending conveyer mounted upon the frame of the machine and including a conveyer 110
- 55 15. In a stone gathering machine, a supporting frame, an axle rotatably mounted in the frame, traction wheels rotating with the axle, said axle being many-sided in cross section, a downwardly and forwardly extending rake operatively supported upon the axle and disposed rearward thereof, a plurality of disks mounted upon the axle to rotate therewith, each disk formed in two sections and each disk having a plurality of inwardly extending recesses, the dividing line between the two sections extending across two of said recesses, said disks being set upon the axle so as to break joints, bolts passing longitudinally through all of said disks and disposed through said recesses, a plurality of sets of lifting teeth operatively pivoted to said bolts, springs disposed in the recesses and holding the lifting teeth in a normal position but yielding against impact of the lifting teeth with stones, each set of lifting teeth being spaced from the adjacent sets, sleeves loosely surrounding the disks and disposed between the lifting teeth, downwardly and forwardly extending stone conveying bars attached to said sleeves and between which the lifting teeth pass, a transversely extending conveyer mounted upon the frame of the machine and including a conveyer 115
- 60 16. In a stone gathering machine, a supporting frame, a transversely extending rotatable axle mounted on the frame, traction wheels operatively connected to the axle to rotate therewith, said axle being square in cross section for a portion of its length, a rake comprising downwardly and forwardly extending rake teeth operatively supported upon the axle and disposed rearward thereof, a plurality of disks mounted upon the axle to rotate therewith, each disk formed in two sections and each disk having a plurality of inwardly extending recesses, the dividing line between the two sections extending across two of said recesses, said disks being set upon the axle so as to break joints, bolts passing longitudinally through all of said disks and disposed through said recesses, a plurality of sets of lifting teeth operatively pivoted to said bolts, springs disposed in the recesses and holding the lifting teeth in a normal position but yielding against impact of the lifting teeth with stones, each set of lifting teeth being spaced from the adjacent sets, sleeves loosely surrounding the disks and disposed between the lifting teeth, downwardly and forwardly extending stone conveying bars attached to said sleeves and between which the lifting teeth pass. 120

In testimony whereof I hereunto affix my signature in the presence of two witnesses.
